UNITED STATES PATENT OFFICE.

PAUL RISSMANN, OF DETROIT, MICHIGAN, ASSIGNOR TO FISHER BODY CORPORATION, OF DETROIT, MICHIGAN, A CORPORATION OF NEW YORK.

CORD ANCHOR.

Application filed May 18, 1921. Serial No. 470,647.

To all whom it may concern:

Be it known that I, PAUL RISSMANN, a citizen of the United States, residing at Detroit, in the county of Wayne and State of Michigan, have invented certain new and useful Improvements in Cord Anchors, of which the following is a specification.

This invention relates to robe cords and "pull to's" for doors. In place of the familiar robe rail there is more commonly used now in automobile body construction a cord suitably trimmed in the material with which the body is trimmed. It is the object of the present invention to provide a suitable anchor for the end of the trimmed cords used in automobile bodies. This anchor is a very effective one and yet at the same time is relatively simple and economical in construction. The anchor not only prevents the cord from being drawn out of the fixture but it also prevents the cord turning in the fixture so as to expose the seam of the upholstery, which should be carried on the inside of the cord where it cannot be seen.

In the drawings.—

Fig. 1 is a view of the rear seat of an open body car showing the robe cord in place.

Fig. 2 is a plan view of one of the fixtures for attaching the cord to the seat-back showing a fragment of the cord.

Fig. 3 is an end view of the fixture and a section of the cord.

Fig. 4 is a longitudinal section of the fixture and an elevation of the cord and anchor.

Fig. 5 is a perspective of the anchor.

a designates an upholstered cord. The specific construction of the cord is no part of the invention, hence is not illustrated in detail. Let it suffice to say that the cord is made up of any suitable material and on the same is sewed a cover *b* usually of the same trimming material that is used on the inside of the body, usually some kind of velour, plush or the like.

c designates the fixture, which comprises an ornamental drawn metal plate of the general contour shown in Figs. 2, 3 and 4. It has a base portion *d* provided with struck-in countersunk portions *e* to receive the screws by which it is fastened to the back of the seat or to a door, if used as a "pull to." It has a center portion which is struck up into the hollow boss having at one end of the boss an opening *f* which just fits the

cord with the upholstery on it. The cord may be threaded through this opening. The anchors may be placed on the ends of the cord after the two fixtures have been threaded onto the cord, or for that matter, one anchor may be placed on the cord before it is threaded through either fixture. The second anchor, however, will have to be placed upon the cord after both fixtures have been threaded upon the cord. This may be easily done as the fixtures may be run up on the cord to expose the end for the anchor.

The anchor comprises simply a pair of channel plates *h*, *h*. The channel plates are exactly the same construction and can be made on a single die. At the center they have a prong *i* struck out of the material. The cord may be punched by a suitable punch in two places. This will ordinarily be a machine operation. Thereupon the plates may be inserted in a suitable press which drives the prongs through the cord and through the slot in the companion channel plate and bends the ends of the prongs over as is clearly shown in Fig. 4. The channel plates are rectangular in cross section and are also larger than the opening *f* through the end of the boss, as is clearly shown in Fig. 2. The consequence is that after the anchor has been clamped to the end of the cord the cord cannot be drawn through the opening. Furthermore, it will be seen that the boss has a cross section which is flattened at the sides. The anchor, as appears in Fig. 2, fits fairly snugly within this cross section. Consequently, the anchor being rectangular in cross section, it holds the anchor from turning.

When the anchor is placed upon the cord it is placed so that the seam *x* of the cover will remain on the inside of the cord. Hence when the fixtures are secured to the back of the seat by screws the cord is held in place so that it cannot pull out or turn in the fixtures. Obviously when the fixtures are screwed down on the back of the seat this holds the cord end from drawing any further into the fixture. Consequently this pair of simple channel plates with the upstanding prongs securely locks the cord ends in the fixtures. Furthermore, it serves to hold the end of the cord and the cover from fraying out.

It will be obvious that the device is both economical and lends itself to fast production on a large scale as the clamping plates

may be made simply as stampings on a single die. The plates may be assembled onto the ends of the cord by a suitable machine for that purpose.

5. What I claim is:

1. In a support for trimmed cords, the combination of a fixture for securing to a support and comprising a plate having a boss raised at its center and provided with an opening at one end of the boss into the hollow interior, a trimmed cord passing through said opening, and a two-part clamp secured and clinched on the end of the cord and shaped to prevent being drawn through said opening, said clamp contained within the interior of said boss for anchoring the cord and clamp within the fixture.
10. In a support for a cord, the combination of a fixture comprising a plate provided with a hollow interior portion having an opening thereto, a cord passing through said opening, and a clamp shaped to prevent being drawn through said opening and located within the hollow interior of said plate, said clamp comprising a pair of channel members, and means for securing the same together and to the cord.
15. In a support for a cord, the combination of a fixture comprising a plate having a hollow interior with an opening thereto, a cord passing through said opening, and

a clamp secured to the end of the cord and normally engaging in said hollow interior, said clamp being composed of a pair of channels having prongs struck out and impaled through the cord and turned over to clamp the two channels together on opposite sides of the cord, the said clamp being shaped to prevent being drawn through said opening in the plate.

35. 4. In a support for a cord, the combination of a fixture having a boss which has a non-circular cross section and an opening in the end of the boss, a cord passing through the opening in the end of the boss, and a two-part clamp each part secured and clinched onto the end of the cord and of rectilinear cross section adapted to fit into said boss and be shaped to prevent turning in the said boss and also to prevent being drawn through the opening in the end of the said boss of said fixture.

40. 5. In a support for trimmed cords, the combination of an anchoring member having a hollow interior fixed to a support and provided with an opening, a trimmed cord passing through said opening, and a two-part clamp clinched onto the end of the cord to prevent the said cord from being withdrawn from the anchoring member.

45. 60. In testimony whereof I affix my signature.

PAUL RISSMANN.
